CLAIM

The ornamental design for a bottle, as shown and described.

DESCRIPTION

FIG. 1 is a perspective view of a bottle showing our new design;

FIG. 2 is a front view of the bottle depicted in FIG. 1, the rear and side views are the same except for the placement of the indentations on the base;

FIG. 3 is a side view of the bottle depicted in FIG. 2 representing a partial rotation of the bottle about its vertical center axis from the front view depicted in FIG. 2; and, FIG. 4 is a bottom view of the bottle depicted in FIG. 2. The broken lines showing the upper portion of a bottle are for illustrative purposes only and do not form part of the claimed design.
